UNITED STATES PATENT OFFICE.

JOSEPH E. STRAKER, JR., OF ATTLEBORO, MASSACHUSETTS.

DESIGN FOR A BORDER FOR SILVERWARE.

No. 39,588.

Specification for Design.

Patented Sept. 29, 1908.

Application filed May 12, 1908. Serial No. 432,505. Term of patent 7 years.

To all whom it may concern:

Be it known that I, JOSEPH E. STRAKER, Jr., a citizen of the United States, and residing in the town of Attleboro, in the county of Bristol and Commonwealth of Massachusetts, have invented a new, original, and ornamental Design for a Border for Silverware, which is illustrated in the accompanying drawings, forming part of this specification.

Figure 1 is a plan view showing the design of the border and Fig. 2 is a perspective showing the design of the border.

The material feature of my design consists in the ornamentation of the border by the artistic arrangement of quadrilateral figures and parallel lines.

In detail the border consists of a centrally

disposed convex surface, seen in Fig. 2, transversely placed in which is a series of approximately parallel quadrilateral figures seen in Fig. 1. Along one edge of this surface extends an elevated molding surrounded by a raised thread forming the outer edge of the border. The inner edge of the border consists of a smooth flat molding which is separated from the convex surface by a raised three thread molding.

What I claim is:—

The ornamental design for a border for silverware as shown and described.

JOSEPH E. STRAKER, JR.
